PORTABLE HAND SANDING TOOL

Francis D. Dolan, Toledo, Ohio, assignor to The American Floor Surfacing Machine Company, Toledo, Ohio, a corporation of Ohio

Application August 5, 1954, Serial No. 31,749

Term of patent 3½ years

(Cl. D37—1)

FIG. 1.

FIG. 2.

FIG. 3.

FIG. 4.

FIG. 5.

FIG. 6.

Figs. 1 and 2 are opposite side elevations of a portable hand sanding tool showing my new design;

Figs. 3 and 4 are top and bottom views thereof, respectively, and

Figs. 5 and 6 are rear end and front end views thereof, respectively.

The dominant features of my design reside in the portions shown in full lines.

I claim:

The ornamental design for a portable hand sanding tool, substantially as shown and described.
